VALVE CONTROL

Claude D. Anderson, Jr., Memphis, Tenn.

Application April 18, 1938, Serial No. 202,665

14 Claims. (Cl. 236—74)

The present invention relates to the automatic control of valves, such as those used to control the flow of fuel to a burner as for instance, a gas valve.

5 It particularly relates to valve controls, which accomplish a plurality of open positions of the valve which range from full flow opening to partial flow opening.

In order to obtain close temperature control, 10 it has been found desirable to move a fuel control valve to a selected one of a plurality of control positions instead of moving such a valve from completely closed position to completely opened position only. The average burner, however, while capable of properly burning a relatively small supply of fuel after such fuel has 15 been initially ignited, requires a much larger flow of fuel for proper ignition. This is particularly true of gas burners wherein, if the initial supply 20 of fuel is too small, the flame will "pop back" and the gas will burn in the mixer. In order to overcome this difficulty in installations where a pilot light is used, and still make it possible to vary the supply of fuel to a burner, it has heretofore 25 been proposed and attempted to arrange the control system in such manner that upon an initial demand for a relatively small amount of fuel, the valve mechanism is opened widely for a short period, to furnish a sufficiently large supply of 30 fuel for proper ignition, and is then partially closed to supply a smaller amount of fuel which is more nearly in accordance with the demand. In this manner, upon a demand for a small amount of fuel which is sufficiently large to burn 35 properly after having been ignited, but is insufficient for the establishment of proper ignition, a large supply of fuel capable of being properly ignited is initially provided and this supply is then automatically reduced to correspond to the 40 demand.

The objects of my invention are:

To provide, in connection with a valve for controlling the flow of fuel gas from a source of supply to a burner, means responsive to a drop 45 in temperature to a predetermined point for opening the valve, and to rising temperature for closing the valve.

To provide in connection with such a valve, having operating mechanism, and initiating and 50 terminating means; means for determining at which of a plurality of open or partially open positions the valve shall be maintained, during such temperature determined period.

To provide valve opening means adapted to 55 fully open the valve, maintain such valve fully

open during a limited period and thereafter partially close same, and means to determine desired partial closure points.

To provide means having a continuous movement for opening and thereafter partially closing 5 a valve, means for stopping said movement at a desired position of valve opening; and

To provide a device of this character which is positive in action and simple in construction.

The means by which the foregoing and other 10 objects are accomplished and the method of their accomplishment will readily be understood from the following specifications on reference to the accompanying drawings, in which:

Fig. 1 is a front elevation with cover parts 15 broken away and the valve shown in section, and with a diagrammatic lay-out for the wiring and related temperature control means.

Fig. 2 is a side elevation with the cover broken 20 away.

Referring now to the drawings in which the various parts are indicated by numerals:

10 is a valve for controlling flow of gas from a suitable source of supply to a burner or burners. The supply source and the burners are not a part 25 of the present invention, and are therefore not shown. The valve 10 has a seat 11 and a disc 12 adapted to be raised to establish flow. 13 is a valve stem which extends through a suitable stuffing box 14 and is connected through a bracket link 15 and pin 16 to a connecting rod 17. 18 is a crank pin which is carried by a gear 19 which serves as a crank disc or arm. The gear 19 turns on an axle shaft 20 which projects from a frame member or plate 21. In the operation of the 35 mechanism a one-half turn of the gear 19 only is employed. The gear 19 meshes with a pinion 25 forming part of a gear train through which the gear 19 is driven at greatly reduced speed by a motor 26. 40

The plate 21 has mounted thereon magnets 30, 31 with which magnets are associated members 32, 33, respectively, which have shoulders or stops 34, 35, respectively. Preferably the magnet 30 is fixedly mounted on the plate 21 and the magnet 45 31 is adjustably mounted to provide a positioning adjustment, this adjustment being accomplished through a pair of clamping screws 36 which project from the plate 21 and are disposed through slots 37 in ears 38. 39 is a bracket, suitably secured to the plate 21, this bracket having an integral arm 40 which projects over the face of the gear 19 and carries an adjustable stop screw 41. 50

45 is an armature of suitable magnetic metal hingedly secured as by a pin 46 to the gear 19. 55

47 is a tension spring retracting the armature 45 against a stop pin 43. The armature 45 when moved by the gear 19 into the magnetic field of action of either of the magnets 30 or 31, is on energization of such magnet drawn outward into the path of the corresponding shoulder 34, or 35, and thereby stops movement of the gear. 49 is a stop secured to the gear 19 and moving therewith against the stop screw 41 to stop the gear, where previous stoppage, by one or the other magnet stop, has not been effected.

50 is a spring having one end 51 engaging a pin 52 projecting from the gear 19 and its opposite end 53 engaging a pin 54 which projects from the plate 21, movement of the gear 19 being resisted by this spring, and return movement of the gear accomplished when the gear is released, such return movement of the gear, moving the crank pin 18 to initial position and closing the 10 valve disc against its seat, and also through the gear train reversely rotating the motor.

50 is a power circuit, 61 a transformer through which reduction from line voltage to a lower operating voltage is accomplished, and 62 a transformer-coupled power circuit. One leg 63 of this latter circuit leads through the motor 26 and a lead 27 to a contact point 28. 29 is a second contact point from which a lead 30 extends to a switch bar 31, this switch bar being shiftable, 20 manually or otherwise, to any one of three poles 32, 33 or 34, in the present view, the switch bar being shown in contact with the pole 32. From the pole 32, a lead 35 extends to the magnet 30 and from this magnet a lead 36, 37, and 38 completes an open circuit. From the pole 33 a lead 40 extends to the magnet 31 and from this magnet a lead 41 extends to a connection with the lead 37 and through this lead and the lead 38 completes a second open circuit. From the pole 34 a lead 42 connects to the lead 38 and completes a third open circuit.

43 and 44 are resilient contact bars electrically connected and adapted to seat against the contacts 28 and 29 and close any selected one of 45 these circuits. The contact bars 43, 44 are controlled by a thermostat 45 of well known type and are closed by response of this thermostat to a drop in temperature to some chosen degree.

50 It will be understood that the double contact illustrated is what is known as a delayed cut-off type, but the action of the thermostat and the question of delayed or other type of cut-off having no particular connection with the present invention need not here be detailed.

55 The switch bar 31 is manually shiftable to any of the three poles 32, 33 or 34 and is shifted to adjust the operation of the device to outside temperatures, the switch bar being shifted, as shown, to the contact 32 when the outside temperature is low, or shifted to the pole 33 when the temperature is somewhat more moderate, and to the pole 34 when the temperature is higher.

60 In using the device, if the temperature outside is extremely low, switch bar 31 is shifted to the pole 32 as shown, thus establishing the motor circuit through the magnet 30 from the power line 60. If the temperature to which the thermostat is responsive drops to some predetermined point, as around 70 degrees, the contact bars 43 70 and 44 are closed against the contacts 28 and 29, and the previously open circuit to the motor 26 thereby closed, putting the motor in operation, and through the train of gearing and the pinion 25, turning the gear 19 clockwise, as seen in 75 Fig. 1. Turning movement of the gear continues

until the armature 45 approaches the position 45A and is drawn out by action of the energized magnet 30, into position to engage the stop 34, stop the movement of the gear, and stall the motor. As the gear moves from initial position 5 toward this stop the crank pin 18 moves to the position 18A, raising the valve disc 12. By such movement the disc 12 is sufficiently raised to give an opening between the disc and valve seat 11, equivalent to the area of the opening through 10 the valve seat, or in other words, the valve is opened to its maximum capacity, permitting the burner or burners fed by such valve to burn at such maximum capacity until such time as the thermostat 45, responsive to temperature increase, 15 breaks the circuit through the contacts 28, 29 and cuts off current flow both to the magnet and the motor. With current flow to the motor cut off the spring 50 reversely shifts the gear 19 and closes the valve disc 12 against the 20 seat 11. In this reverse movement the gear, through pinion 25, and train of gearing, reversely turns the motor.

25 If a more moderate weather temperature exists, the switch bar 31 is shifted to the contact 33, thus establishing the motor circuit through the magnet 31, which circuit is closed on response of the thermostat, to a temperature drop as before. The motor so energized turns the gear 19 until the armature 45 reaches the dotted position 45B, is drawn out by action of the magnet 31, and stopped by the stop 35. During this movement the crank pin 18 moves through the position 18A, fully opening the valve, and holds this valve fully open until it reaches the position 18B, after which it slowly closes the valve until it reaches and is stopped at the position 18C. In this manner a full flow of gas is established through the valve 10 obviating any chance that the pilot light will not ignite the gas. The 30 valve is held open for a sufficient time to absolutely insure ignition and thereafter is partially closed to reduce the intensity of the burner flame. Again the valve is held in such opened position until the thermostat, in response to rising temperature, breaks the circuit and cuts off current flow to the motor allowing the spring 50, as before, to reversely turn the gear and close the valve, and, as before, reversely turning the motor.

35 If the weather temperature is still higher the switch bar 31 may be shifted to the pole 34 and the third circuit established, which by-passes both magnets. Closure of this circuit by the thermostat, starts the motor, and, as before, turns the gear, opening the valve, holding it open and then slowly closing it until the stop 49 reaches the position 49A and the crank pin 18 reaches the position 18D, subsequent actions being identical with those before described.

40 It will be understood that the screw 41 may be adjusted to very delicately regulate the last positioning 18D of the pin 18, and also that the magnet 31 may be shifted by loosening the screws 36 to adjust the positioning of this magnet and of the cut-off point 18C.

45 I claim:

1. Valve control means, including electrically operable means for opening said valve, said means progressively continuing movement of said valve through full open and toward closing; means urging retrogressive movement of said operable means, said retrogressive urging means acting through said operable means to accomplish retrogressive movement of said valve to 50

closed position, means for stopping said valve in substantially full open position, means adapted for stopping said valve in a progressive position of partial closure, and means cooperating with said electrical means, for selectively rendering said stop means effective.

2. Valve control means, including electrically operable means for opening said valve said means progressively continuing movement of said valve through full open and toward closing; means urging retrogressive movement of said operable means, said retrogressive urging means acting through said operable means to accomplish retrogressive movement of said valve to closed position; means for stopping said valve in substantially full open position, means adapted for stopping said valve in a progressive position of partial closure, and an additional means for limiting progressive movement toward closure, and means cooperating with said electrical means, for selectively rendering said stop means effective.

3. Valve control means, including electrically actuatable means for opening said valve and progressively continuing movement of said valve through full open and toward closing position, means resiliently urging return movement of said actuating means, said resilient means functioning through said actuating means to retrogressively return said valve to closed position, electrically energizing means adapted respectively for stopping said valve in substantially full open position, and in a progressive position of partial closure; and an additional means for limiting progressive movement toward closure, and means cooperating with said electrical means, for selectively rendering said electrically energizable means effective.

4. A device of the character described including a valve, a member movable progressively along a continuous path, and actuatable coupled to said valve to progressively, fully open, hold open and reduce the opening of said valve, means for limiting said reduction of opening; electrically actuatable means for moving said member along said path, a normally open power circuit leading to said electrical means; electrically energizable means, each for stopping said member at a predetermined point in its movement, selective means for shunting said circuit through a desired one of said electrically energizable means; resilient means for retrogressively turning said member and valve to closed position, on cessation of current flow; and temperature controlled means for closing and opening said circuits.

5. A device of the character described including a valve, a member movable along a continuous predetermined path, and actuatable coupled to said valve to progressively, fully open, hold open and reduce the opening of said valve; electrically actuatable means for moving said member along said path, a normally open power circuit leading to said electrical means; electrically energizable means, each for stopping said member at a predetermined point in its movement, selective means for shunting said circuit through a desired one of said electrically energizable means; resilient means for retrogressively turning said member and valve to closed position, on cessation of current flow, and temperature controlled means for closing and opening said circuits.

6. A device of the character described including a valve, a rotatable member actuatable coupled to said valve to progressively, fully open,

hold open and reduce the opening of said valve; electrically actuatable means for turning said member, a normally open power circuit leading to said electrical means; electrically energizable means, each for stopping said member at a predetermined point in its rotation, selective means for shunting said circuit through a desired one of said electrically energizable means; resilient means for retrogressively turning said member and valve to closed position on cessation of current flow; and means for closing and opening said circuits.

7. A device of the character described including a valve, a rotatable member actuatable coupled to said valve to progressively, fully open, hold open and reduce the opening of said valve, means for limiting said reduction of opening; electrically actuatable means for turning said member, a normally open power circuit leading to said electrical means; electrically energizable means, each for stopping said member at a predetermined point in its rotation, selective means for shunting said circuit through a desired one of said electrically energizable means; resilient means for retrogressively turning said member and valve to closed position on cessation of current flow; and means for closing and opening said circuits.

8. A device of the character described including a valve, a crank disc rotatably mounted, a crank pin projecting from said disc, a connecting rod operably connecting said pin and said valve, a spring acting on said disc, and through said pin and rod to hold said valve in closed position, an electric motor, a train of speed reduction gearing actuatable coupling said motor and disc to turn said disc against said spring action, and progressively open and reduce opening of said valve, a stop limiting progress of said disc at a predetermined reduction of said valve opening; a plurality of stop means each at a predetermined intermediate position of movement of said disc, said stop means each having an associated electrically energizable means for rendering it effective; a normally open power circuit leading to said motor, means for shunting said circuit through a selected one of said energizable means, and temperature controlled means for closing and opening said circuit.

9. A device of the character described including a valve, a rotatably mounted crank means including a crank pin, a connecting rod operably connecting said pin and said valve, a spring acting on said crank means and through said rod to hold said valve in closed position; an electric motor, a train of speed reduction gearing coupling said motor and crank means to turn said means against said spring action, and progressively open and reduce opening of said valve, a stop limiting progress of said means at a predetermined reduction of said valve opening; a plurality of stop means at predetermined intermediate positions of movement of said crank means, said stop means each having an associated electrically energizable means for rendering it effective, a normally open power circuit leading to said motor, means for shunting said circuit through a selected one of said energizable means, and temperature controlled means for closing and opening said circuit.

10. Valve control means including a valve having a seat and a disc movable toward and away therefrom; a valve rod extending exterior to said valve and reciprocatable to raise and lower said valve from its seat, a frame mounted above said

valve, a disc gear rotatably mounted on said frame, a crank pin extending from said gear and a connecting rod coupling said valve rod and crank pin, a spring having one end engaging said frame and its opposite end engaging said gear for retrogressive movement of said gear, a stop carried by said gear, a cooperative stop carried by said frame; a motor and a train of reduction gearing connecting said motor and said gear; a pair of electro-magnets mounted on said frame in proximity to the periphery of said gear, each of said magnets having an associated stop member, an armature pivotally carried by said gear, and movable by rotation of said gear past said magnets, said armature being adapted to be shifted into engagement with either said magnet stop upon energization of its respective magnet, a spring secured to said gear and retractively engaging said armature; means carried by said gear limiting said retractive movement; a power circuit leading to said motor, said circuit including an automatic switch for closing and opening said circuit; circuit means respectively leading to said electro-magnets, and a switch selectively operable to shunt said motor circuit through either of said magnets.

11. Valve control means, including a valve having a seat and a disc movable toward and away therefrom; a valve rod extending exterior to said valve and reciprocatable to raise and lower said valve from its seat, a frame mounted above said valve, a disc gear rotatably mounted on said frame, a crank pin extending from said gear, a connecting rod coupling said valve rod and crank pin, resilient means cooperating with said frame and said gear for retrogressive movement of said gear, said retrogressive movement being limited by seating of said valve disc, a stop carried by said gear, a cooperative stop carried by said frame for limiting progressive gear movement; a motor and a train of reduction gearing connecting said motor and said gear; a plurality of electro-magnets mounted on said frame in proximity to the periphery of said gear, each of said magnets carrying an associated stop member, an armature pivotally carried by said gear, and movable by rotation of said gear past said magnets, said armature being adapted to be shifted into engagement with either said stop member upon energization of its respective magnet, a spring secured to said gear and retractively engaging said armature; means carried by said gear limiting said retractive movement, a power circuit leading to said motor, said circuit including a thermostatically controlled switch for closing and opening said circuit and a second switch, open circuit means respectively leading from said motor circuit to said electro-magnets, said second switch being selectively operable to shunt said motor circuit through said magnet circuits.

12. A device of the character described including a valve, a crank disc rotatably mounted, a crank pin projecting from said disc, a connecting rod operably connecting said pin and said valve, a spring acting on said disc, and through

said pin and rod to hold said valve in closed position, an electric motor, a train of speed reduction gearing actuatably coupling said motor and disc to turn said disc against said spring action, and progressively open and reduce opening of said valve; a plurality of stop means each at a predetermined intermediate position of movement of said disc, said stop means each having an associated electrically energizable means for rendering it effective; a normally open power circuit leading to said motor, means for shunting said circuit through a selected one of said energizable means, and temperature controlled means for closing and opening said circuit. 5

13. A device of the character described including a valve, a rotatably mounted crank, means including a crank pin, a connecting rod operably connecting said pin and said valve, a spring acting on said crank means and through said rod 20 to hold said valve in closed position; an electric motor, a train of speed reduction gearing coupling said motor and crank means to turn said means against said spring action, and progressively open and reduce opening of said valve; 25 a plurality of stop means at predetermined intermediate positions of movement of said crank means, said stop means each having an associated electrically energizable means for rendering it effective, a normally open power circuit 30 leading to said motor, means for shunting said circuit through a selected one of said energizable means, and temperature controlled means for closing and opening said circuit.

14. Valve control means including a valve having a seat and a disc movable toward and away therefrom; a valve rod extending exterior to said valve and reciprocatable to raise and lower said valve from its seat, a frame mounted on said valve, a disc gear rotatably mounted on said frame, a crank pin extending from said gear and a connecting rod coupling said valve rod and crank pin, a spring having one end engaging said frame and its opposite end engaging said gear for retrogressive movement of said gear; a motor and a train of reduction gearing connecting said motor and said gear; a pair of electro-magnets mounted on said frame in proximity to the periphery of said gear, each of said magnets having an associated stop member, an armature pivotally carried by said gear, and movable by rotation of said gear past said magnets, said armature being adapted to be shifted into engagement with either said magnet stop upon energization of its respective magnet, a spring secured to said gear and retractively engaging said armature; means carried by said gear limiting said retractive movement; a power circuit leading to said motor, said circuit including an automatic switch for closing and opening said circuit; circuit means respectively leading to said electro-magnets, and a switch selectively operable to shunt said motor circuit through either of said magnets. 40
